[57] CLAIM

An ornamental design for a ribbon cassette for type-
writer or the like, as shown.

DESCRIPTION

FIG. 1 is a rear elevational view of a ribbon cassette for
a typewriter or the like showing my new design;
FIG. 2 is a top plan view thereof;

FIG. 3 is a front elevational view thereof;

FIG. 4 is a left side elevational view thereof;

FIG. 5 is a bottom plan view thereof;

FIG. 6 is a right side elevational view thereof; and

FIG. 7 is a perspective thereof.
